UNITED STATES PATENT OFFICE.

GILES F. WILLIAMSON, OF SAVANNAH, GEORGIA.

CLOSURE FOR BARRELS, &c.

No. 918,718.

Specification of Letters Patent.

Patented April 20, 1909.

Application filed August 10, 1908. Serial No. 447,798.

To all whom it may concern:

Be it known that I, GILES F. WILLIAMSON, citizen of the United States, residing at 536 State street, (now 515 Bay street east,) Savannah, in the county of Chatham and State of Georgia, have invented certain new and useful Improvements in Closures for Barrels, &c., of which the following is a specification.

This invention relates to barrels, casks or 10 the like, and closures therefor.

The object of my invention is to provide for the re-use of barrels, casks, etc. and this object I attain by so constructing the head end of the barrel, and the head proper that 15 the latter may be clamped tightly into position to close the barrel or removed therefrom. Heretofore this object was sought to be attained by forcing the head in wedging sections to be expanded into the croze, or by 20 forming an annular seat for the head well below the chime to receive the edges of the circular head provided with wedge shaped flanges engaging wedge blocks secured within the barrel mouth. These constructions are 25 considered objectionable in that the parts cannot be readily cleansed for re-use, owing to the movable wedging parts, or the sharp non-accessible angles beneath the wedge blocks within the barrel mouth.

30 My invention consists in the combination with a barrel provided at its mouth or open end with a permanently seated annulus having a wide elliptical opening of a head adapted to tightly fit the annulus and provided on 35 its inner side with undercut shoulders adapted to pass through the longer radius of the opening in annulus and lock beneath the narrower radius thereof.

In the accompanying drawings—Figure 1, 40 is a top plan view of a barrel, illustrating a part of the closure. Fig. 2, is a vertical sectional view on the line 2—2, Fig. 1, showing the upper part of a barrel embodying my improvements, the closure being in unlocked 45 position. Fig. 3, is a similar section taken on the line 3—3 Fig. 1 showing the parts in locked position. Fig. 4, is a perspective view of the cover, inverted.

My invention is designed particularly for 50 use with barrels casks, firkins etc., formed of thick oak staves, as indicated, though it is applicable, to some extent to flour and sugar barrels, formed of thin staves and to other receptacles, not having the centrally bulged 55 form of barrels or casks, as for instance, the

outwardly flared straight walls of "butter tubs" and the like.

Referring to the drawing the barrel, cask or the like is formed of staves 1, which may be crozed, as shown at 2, Fig. 2, or may be 60 finished without a croze, as shown in Fig. 3.

Fitted tightly within the end of the barrel is a narrow annulus or flange ring 3 preferably of cast iron, the inwardly extending flange thereof terminating to form a large 65 central opening 4 that will give ready access to the contents of the barrel. This opening is of elliptical form, the flange narrowing symmetrically from opposite points 5 of the shorter radius of the opening to points 6 at 70 the longer radius thereof, the edge of the flange increasing in thickness from the points 6 to the points 5, thereby forming symmetrical inclines from said points 6 to 5, for a purpose to be explained. This annulus may 75 be cast in the form shown in Fig. 2, to fit within the croze of the barrel and be clamped therein by driving the hoops in a manner well understood, or as shown in Fig. 3, wherein no croze is formed in the staves and the 80 periphery of the annulus is securely bolted to the staves, but in any event, the annulus is cast in such form that when in position its inner surface will meet the inner surface of the staves at an acute angle, thereby preventing the lodgment of particles at the junction of the annulus and staves, and facilitating the thorough cleansing of the barrel 85 when emptied.

The barrel cap or head 7 is formed preferably of oak planking of a diameter to fit snugly but not tightly within the barrel, its under surface resting on the inwardly projecting flange of the annulus, as shown. To the under surface of the head is secured a 90 locking means designed to engage the wedge shaped perimeter of the flange, and here shown in the form of a cleat 8 having undercut ends 9 that will pass readily through the 95 elliptical opening of the annulus on the longer radius of the ellipse, as in Fig. 2, but lock with a wedging action beneath the edges of the flange as they become thicker toward the point 5 of shorter radius of the 100 elliptical opening, as shown in Fig. 3. 105

The barrel head may be formed of two or more sections, in which case I prefer to employ the locking cleat 8, as it greatly adds to the strength of the head, being secured with the grain at right angles, to that of the head 110

proper, but it will be understood that this locking means may be formed of two short blocks, as indicated in dotted lines in Fig. 4.

To give additional strength to the head, 5 and also to afford means for readily giving it a partial turn to lock it in position or remove it, I secure to the upper surface two cleats 10 and 11, the grain running at right angles to that of the head, and the adjacent 10 margins being spaced apart to form a parallel sided channel 12, to receive a lever by which the head may be rotated.

By the construction described it will be seen that the barrel may be readily discharged of its contents, as the annulus extends but slightly within the barrel and is arched outward to facilitate the flow of viscid liquids. The margins of the opening in the annulus being smooth, a workman can 20 readily use a paddle or other utensil to clear the barrel of slow flowing liquids, such as turpentine and molasses, without hindrance, and there being no inwardly projecting angular parts, the barrel may be thoroughly 25 cleansed.

I claim,

1. A device of the character described, comprising a head or end member having a filling and emptying opening therethrough 30 and inclined upwardly and inwardly from the inner surface of said receptacle toward the margin of said opening, and a closure or cover adapted to close said opening and rest upon the upper edge of said head-member 35 and provided upon its underside with a cleat having beveled ends or edges taking under said upwardly and inwardly inclined portions of said closure, said closure having upon its upper surface spaced-apart cleats 40 adapted to receive between them a lever for turning said closure into, or out of locked position.

2. A device of the character described, comprising a head or end member having an 45 elliptical filling and emptying opening therethrough and inclined upwardly and inwardly from the inner surface of said receptacle toward the margin of said opening and a closure or cover adapted to close said open- 50 ing and having a cleat upon its underside whose length is less than the major axis or radius of said opening but greater than the cross-section of said opening, said cleat also having beveled ends or edges taking under

said upwardly and inwardly inclined surface 55 of said head-member, the marginal portions or edges around said opening being received within the undercut recesses formed between said beveled edges of the cleat and the overlying or projecting portion of said clo- 60 sure.

3. A device of the character described, comprising a receptacle having an end or head member provided with an elliptical opening and inclined upwardly and in- 65 wardly from the inner surface of said recep- tacle toward the margin of said opening and a closure or cover adapted to close said open- 70 ing and rest upon the upper edge of said head member and provided upon its under- side with a cleat whose length is less than the major axis or radius of said opening but greater than the cross-section of said opening, said cleat also having beveled ends or edges taking under said upwardly and 75 inwardly inclined surface of said head-member, the marginal portions or edges around said opening being received within the under- cut recesses formed between said beveled edges of the cleat and the overlying or pro- 80 jecting portion of said closure, said closure also having upon its upper surface spaced- apart cleats adapted to receive between them a bar or lever for turning said closure into or out of locked position. 85

4. A device of the character described, comprising a receptacle having an end or head member provided with an elliptical opening and inclined upwardly and inwardly from the inner surface of said receptacle 90 toward the margin of said opening, and a closure or cover adapted to close said open- 95 ing and rest upon the upper edge of said head- member, and provided upon its underside with a cleat having beveled ends or edges taking under said upwardly and inwardly inclined portions of said closure, the mar- 100 ginal portions or edges around said opening being received within the undercut recesses formed between said beveled edges of the cleat and the overlying or projecting portion of said closure.

In testimony whereof I affix my signature, in presence of two witnesses.

GILES F. WILLIAMSON.
